UNITED STATES PATENT OFFICE

122,706

DESIGN FOR A CIGARETTE DISPENSER OR SIMILAR ARTICLE

Francis M. Aimes, Yonkers, N. Y.

Application May 25, 1940, Serial No. 92,584

Term of patent 3½ years

To all whom it may concern:

Be it known that I, Francis M. Aimes, a citizen of the United States of America, residing in Yonkers, county of Westchester, and State of New York, have invented a new, original, and ornamental Design for a Cigarette Dispenser or Similar Article, of which the following is a specification, reference being had to the accompanying drawing, forming part thereof, wherein, dispenser shown in Figures 1 and 2.

The rear of the cigarette dispenser is substantially the same in appearance as the front.

I claim:

The ornamental design for a cigarette dispenser or similar article, substantially as shown, and described.

FRANCIS M. AIMES.
